UNITED STATES PATENT OFFICE.

HARRY M. PFLAGER, OF ST. LOUIS, MISSOURI, ASSIGNOR TO DOUBLE BODY BOLSTER COMPANY, OF ST. LOUIS, MISSOURI, A CORPORATION OF NEW JERSEY.

CAR END FRAME.

1,072,616.

specification of Letters Patent.

Patented Sept. 9, 1913.

Application filed November 8, 1912. Serial No. 730,221.

To all whom it may concern:

Be it known that I, HARRY M. PFLAGER, a citizen of the United States, residing at St. Louis, Missouri, have invented a certain 5 new and useful Improvement in Car End Frames, of which the following is a full, clear, and exact description, such as will enable others skilled in the art to which it appertains to make and use the same, reference being had to the accompanying drawings, forming part of this specification, in 10 which—

Figure 1 is a front elevational view of a car end frame of my improved construction. 15 Fig. 2 is a plan view partly in horizontal section and taken approximately on the line 2—2 of Fig. 1. Fig. 3 is a side elevational view of my improved end frame and showing a portion of the car underframe in dotted lines. Fig. 4 is a vertical section taken 20 approximately on the line 4—4 of Fig. 1.

This invention relates generally to railway car construction, and more particularly to the one-piece, cast metal car end frames 25 of the type disclosed in Patent No. 917,716, issued April 6, 1909 and No. 929,705, issued to me August 3, 1909.

One of the most important features in the construction of the present types of 30 railway cars, and particularly those utilized for the transportation of passengers, mail and express matter and baggage is the reinforcing of the ends of the cars so as to provide an exceptionally strong, rigid construction which will effectually resist end 35 shocks and crushing stresses delivered to the ends of the cars, consequently overcoming the tendency of the cars to telescope in case of collisions, and affording the 40 greatest possible degree of safety to the occupants and contents of the cars.

My improvement contemplates a comparatively light-weight, strong and durable one-piece cast metal structure, formed, 45 braced and connected to the car underframe and superstructure so as to combine therewith in resisting end shocks and crushing stresses imparted to the end of the car, thereby providing a construction which 50 is anti-telescopic in effect.

The principal object of my present invention is to provide a one-piece, cast metal end frame particularly designed for use on

cars utilized for transporting automobiles, carriages, large pieces of theatrical scenery and other large vehicles and objects.

An end frame of my improved construction practically forms a large end door frame for the car body, and by hinging a pair of doors to the sides of the frame a door opening the full width of the car is provided, thus readily permitting large pieces such as automobiles, carriages and large pieces of scenery to be placed in or removed from the car.

A further object of my invention is to provide a cast metal end frame having a comparatively large door opening, and which end frame is constructed so as to be readily combined with the car underframe and superstructure.

To the above purposes my invention consists in certain novel features of construction and arrangement of parts hereinafter more fully described and claimed.

Referring to the accompanying drawings, A designates the car underframe and B the end sill thereof, which latter in the present instance is shown as an integral member of the underframe.

My improved end frame as shown includes a flanged base member 10, preferably L-shaped in cross section, and said base member rests directly upon and is attached to the end sill B, preferably by means of rivets or like fastening devices.

Formed integral with the ends of the base member 10 are upright members 11 which constitute corner posts for the car body, said uprights being flanged and of any desired shape in cross section. The lower portions of these uprights are provided with integral rearwardly extending brackets 12, the lower rear ends of which bear directly against shoulders 13 formed on the underframe, which arrangement relieves the rivets utilized in fastening the base member to the underframe of shearing strains, and also holds the end frame against horizontal displacement inwardly.

Formed integral with the outer face of each upright or post 11 is a pair of lugs 14, the same being perforated vertically so as to receive the pins carried by the hinges on the car end doors.

Formed integral with the upper ends of

the uprights 11 is a horizontally disposed top rail 15, the same being flanged for strengthening purposes, and of any desired cross-sectional shape. The end portions of this rail 15 are inclined downward, as designated by 16, and at the points where said downwardly inclined ends unite with the uprights 11, L-shaped seats 17 are formed for the ends of the side plates of the car body. Formed integral with the end portions of the rail 15 are upwardly projecting brackets or flanges 18, to which parts of the car roof structure are attached.

An end frame of my improved construction, being cast in a single piece, can be very cheaply produced as compared to an end frame of built-up construction for the reason that much time, labor and consequent expense is involved in assembling the parts of a built-up frame, and a one-piece cast metal frame is very strong and rigid and combines with the car underframe and superstructure in forming an exceptionally strong construction that is antitelescopic in effect.

An end frame of my improved construction in reality forms the function of a large door frame, and the posts at the sides of the frame which are in reality door posts perform the function of corner posts for the car body.

The opening in the frame is practically the same width as the space between the side walls of the car, and the same height as the space between the floor and car roof, and thus comparatively large vehicles or comparatively large objects such as pieces of theatrical scenery can be readily taken into or removed from a car equipped with my improved end frame.

It will be readily understood that minor changes in the size, form and construction of the various parts of my improved end frame can be made and substituted for those herein shown and described without departing from the spirit of my invention, the scope of which is set forth in the appended claims.

I claim:

50 1. The combination with a car body, of a one-piece cast metal end frame having a door opening that is substantially equal in width to the width of the space within the car body and which frame comprises a pair of uprights adapted to serve as corner posts for the car body, a base member connecting the lower ends of said uprights, and a top rail connecting the upper ends of said uprights.

60 2. As a new article of manufacture, an end frame for car bodies comprising a pair of uprights adapted to serve as corner posts for a car body, a base member connecting the lower ends of said uprights and a top rail connecting the upper portions of said up-

rights, all of which parts are cast integral and the entire space between said uprights, base member and top rail being open and unobstructed.

3. The herein-described end frame for car bodies comprising a pair of door posts, brackets on the lower ends of said door posts, which brackets are adapted to engage the underframe of the car on which the end frame is positioned, a base member connecting the lower ends of the uprights, and a top rail connecting the upper portions of said uprights, all of which parts are cast integral.

4. As a new article of manufacture a one-piece end frame comprising a base member, a pair of uprights integral with said base member, rearwardly projecting brackets at the lower ends of said uprights which uprights constitute corner posts for the car body, and a top rail integral with the upper portions of said uprights and the entire space between said uprights, base member and top rail being open and unobstructed.

5. The combination with a car body, of a one-piece end frame comprising a base member, a pair of uprights integral with said base member, which uprights constitute corner posts for the car body, hinge lugs integral with said uprights, and a top rail integral with the upper portions of said uprights.

6. The herein-described car end frame, comprising a flanged base member, a pair of flanged uprights, a pair of hinge lugs on each upright, a flanged top rail between the upper portions of the uprights, all of which parts are formed integral.

7. The herein-described car end frame, comprising a flanged base member, a pair of flanged uprights, brackets projecting rearwardly from the lower ends of said uprights, a pair of hinge lugs on each upright, and a flanged top rail connecting the upper portions of said uprights, all of which parts are formed integral.

8. The combination with a car body, of a cast metal, one-piece end frame having a single door opening that is substantially equal in width to the width of the space within the car body.

9. The herein-described car end frame comprising a pair of uprights having rearwardly extending brackets at their lower ends, a base member connecting the lower ends of said uprights, and a top rail connecting the upper ends of said uprights, the entire space between which uprights, base member and top rail is open and unobstructed.

10. The herein-described car end frame comprising a pair of flanged uprights which constitute corner posts for the car body, brackets fixed to and extending rearwardly from the lower ends of said uprights, a flanged base member connecting the lower

ends of the uprights, and a flanged top rail connecting the upper ends of said uprights, the entire space between which uprights, base member and top rail is open and unobstructed.

5 In testimony whereof I hereunto affix my

signature in the presence of two witnesses, this 22nd day of October, 1912.

HARRY M. PFLAGER.
